UNITED STATES PATENT OFFICE.

EDWIN O. BENTLEY, OF BALTIMORE, MARYLAND.

GAS-CONTROLLING MECHANISM FOR GAS-BURNERS.

1,027,519.

Specification of Letters Patent.

Patented May 28, 1912.

Application filed February 6, 1912. Serial No. 675,729.

To all whom it may concern:

Be it known that I, EDWIN O. BENTLEY, a citizen of the United States, residing at Baltimore, in the State of Maryland, have 5 invented certain new and useful Improvements in Gas-Controlling Mechanism for Gas-Burners, of which the following is a specification.

My present invention pertains to an improved gas-controlling mechanism for gas-burners, the structure being especially adapted for use in connection with the ordinary gas-range.

The invention is illustrated in the annexed 15 drawings, wherein:

Figure 1 is a side elevation of the mechanism shown as applied to a gas stove; Fig. 2 a top plan view thereof, a portion of the stove-frame being broken away; Fig. 3 a 20 transverse vertical sectional view, taken on the line 3—3 of Fig. 2; Fig. 4 a similar view, taken on the line 4—4 of Fig. 2; and Fig. 5 a detail view of the supporting clamp.

The object of the present invention is to 25 produce a structure which may readily be adapted to the ordinary commercial gas stove of to-day, without material change in any of the parts other than the substitution of one form of valve for the ordinary valve 30 or cock which is now employed; that is to say, the introduction of a by-pass valve leading to the pilot burner and the ordinary shut-off valve controlling the supply of gas to the main burner.

35 A number of structures have heretofore been proposed to effect the shutting-off of the gas supplied to the burner when the cooking utensil or receptacle is removed from the burner, permitting the gas to flow 40 at such time through the pilot burner so that the main burner will be automatically relighted when the receptacle is again placed in position. Owing to the small space available for the insertion of such de-

45 vices between the top of the oven and the upper framework of the stove or range, it has been somewhat of a problem to construct a device which could be properly positioned and maintained in its working relation to 50 the other portions of the stove. The present structure, however, solves the difficulty and produces a construction wherein the gas supplied to the main burner will be automatically cut off when the vessel is removed from 55 the stove, and the pilot automatically turned on, the reverse operation taking place when

a vessel or utensil is again placed upon the stove. If desired, the pilot burner may be constantly lighted. The mechanism of the present structure stands well within the confines of the stove-frame, so that there is no danger of the parts being inadvertently operated or actuated or injured.

In the drawings, 1 indicates the upper overhanging portion of the stove-frame, which forms the support for the usual grids or top pieces 2, and 3 denotes the top of the oven. The main gas-supply pipe is indicated by 4, and as usual is adapted to have a series of burners connected therewith, one only being shown in the present instance. The burner may be of any approved type, and is indicated by 5, the air and gas mixture passing into the same through the mixing-pipe 6, supported at its outer end in the air-admission chamber 7, provided, as usual, with regulating slides or valves to control the amount of air which is drawn in by the gas which is discharged into the same in the form of a jet from the main shut-off valve 8. Located between said valve 8 and the main 4 is a second valve 9. The valve 8 is provided with the usual stop-cock handle 10, while the valve 9 is furnished with a downwardly-extending stem 11, connected to or formed as an integral portion of the oscillating plug of said controlling valve 9. The plug of said valve is provided with a thorough-port or passage, affording communication between the main 4 and the valve 8, and with a by-pass 8^a, as shown in dotted lines in Fig. 2, adapted to throw the main 4 into communication with a tube 12.

The outer end of the tube 12 terminates, as shown in Fig. 2, at a point adjacent to the main burner 5 and there forms a pilot burner. The stem 11 of the controlling valve is provided with a crank 13, which is connected with the operative mechanism about to be described.

Secured to the air-mixing pipe 6 is a supporting bracket of the form best shown in Fig. 5. It comprises a body portion 14, of a size adapted to fit around the mixing pipe, and having arms 15 and 16 which may be drawn together by a bolt 17. Extending laterally from the upper portion of the body member 14 is an arm or bracket member 18, provided with a pair of upstanding lugs 19, and at its outer end with a hook-shaped member 20. The lugs and hook-shaped member are bored to provide alined open-

ings. Fulcrumed between the lugs 19 and turning on a pin 21 which extends through the alined openings just referred to, is an arm or lever 22, the outer end of which extends upwardly to a point above the burner 5, and is provided with a spider frame 23, the central portion of which frame is higher than the outer ends of the arms of the frame, said arms lying at a point below the 10 grating or top pieces 2. The opposite end of the lever is provided with a laterally-projecting arm 24 which in turn is secured to the upper arm 25 of an elbow-lever fulcrumed upon the pin 21 in the hook-shaped 15 member 20. Secured to the arm 25 is a weight 26, which overbalances the lever 22 and frame 23, so as to normally hold the spider frame 23 in its elevated position, as shown in full lines in the drawings. The 20 opposite end 27 of the elbow lever extends downwardly toward the top 3 of the oven, and has pivotally connected thereto an actuating bar or link 28, the bar being twisted at its mid-length and provided with 25 an opening into which the upwardly-extending member of the crank-arm 13 passes.

It is thought that the operation of the structure will be apparent from the foregoing and an inspection of the drawings. It may be stated, however, that when a cooking receptacle is placed upon the spider frame 23, it will be depressed or thrown downwardly into the position shown in 35 dotted lines in Fig. 1, thereby rocking the lever 22 and, through the connections above set forth, elevating the weight 26. At the same time, motion will be imparted to the elbow lever, and the valve 9 so turned, 40 through the movement of the bar 28 and the crank 13, that a full passage will be afforded therethrough from the main 4 into the valve 8, which at that time is open, permitting a full flow of gas to pass to the main burner 5. 45 As will be noted, particularly from an inspection of Fig. 1, the parts are all protected against accidental operation, and furthermore, they are so proportioned and arranged that the operative structure may 50 be readily attached to the ordinary mixing tube.

By operating the valve 9 from below, the operation or position of the main valve 8 is in no wise interfered with.

55 The use of a bracket such as shown, that

is, having the lever 22 fulcrumed between one pair of lugs and the elbow lever 25, 27 fulcrumed between the other pair of lugs on the hooked end, renders accuracy or close fitting of the parts unnecessary, and there 60 will be no undue twisting of the mechanism, as otherwise might take place if a single joint were relied upon.

Having thus described my invention, what I claim is:

1. In an automatic cut-off and controlling device for gas-burners of gas-stoves, the combination of a burner; an air-mixing pipe extending therefrom; a bracket secured upon said pipe; a lever fulcrumed upon said bracket, the outer end of said lever extending upwardly to a point above the burner; an elbow-lever likewise fulcrumed upon the bracket; a weight carried by the upper arm of said elbow-lever; connections between 75 said arm and the first-named lever; a valve located between the gas-supply and the air-mixing pipe, said valve being provided with a stem having a crank-arm on the lower end thereof; a bar extending from said crank-arm to the lower end of the depending arm of the elbow-lever; and a pilot burner.

2. In an automatic cut-off and controlling device for gas-burners of gas-stoves, the combination of a main burner; an air-mixing pipe extending therefrom; a bracket adapted to be secured to said pipe, said bracket being provided with a pair of up-standing lugs and a hooked end; a lever fulcrumed between said lugs; a spider frame 85 carried at the upper end of said lever over the burner; an elbow-lever fulcrumed in the hook-shaped end of the bracket; a weight carried by the upper arm of said elbow-lever; a laterally-extending arm carried by 90 the lower portion of the first-named lever; connections between said arm and the upper arm of the elbow-lever; a controlling valve having a stem extending downwardly therefrom and provided with a crank carried at 95 the lower end of said stem; a bar extending from said crank to the lower end of the elbow-lever; and a pilot burner.

In testimony whereof I have signed my name to this specification in the presence of 105 two subscribing witnesses.

E. O. BENTLEY.
